GARMENT

Cornell M. Miller, Cheltenham, Pa.

Application June 27, 1942, Serial No. 448,787

3 Claims. (Cl. 2—224)

My invention relates generally to the garment art, and particularly to that class of undergarments which is generally designated by the term "shorts," which term as used herein is intended to include drawers and women's undergarments which are similar to "shorts."

In its more specific aspects my invention pertains to undergarments such as shorts which have means incorporated therein whereby the waistband may be adjusted to different sizes, and wherein means are provided in conjunction with such adjustable means for reducing girthwise tension when the wearer is seated or in bent over position.

There are instances in the prior art of garments of this general type which are designed with a view to lessening girthwise tension, that is, to provide freedom in the seat and hip portion of the garment, but to my knowledge no one of such garments combines a cooperative organization in a garment of waist size adjustment with girthwise tension reducing means.

Purchasers of garments often select the wrong size garments and must either return them or wear them to their discomfiture. This disadvantage is eliminated in shorts constructed according to my invention, due to the adjustable means with which they are provided, combined with the girthwise tension relaxing characteristics, whereby a pair of shorts so constructed may be adjusted to fit a range of waist measurements and a range of varying girth requirements may be satisfied.

Shorts embodying the features of my invention provide the desired characteristics without resorting to the use of elastic materials of any type. There are many disadvantages inherent in such materials when used in garments, not the least of which is the deterioration thereof due to constant laundering. The elastic also causes the garment to be uncomfortable to the wearer due to its binding action.

In most garments of this type with which I am familiar there is a tendency for the leg portions thereof to ride up on the leg when the wearer is in certain positions. This is uncomfortable and therefore an undesirable action and the tendency has been eliminated in shorts embodying my construction of providing unusual seat expansion without requiring the use of additional material.

It is, therefore, an object of my invention to provide a pair of shorts which is adjustable to fit various waist sizes.

A further object of my invention is to provide

a pair of shorts which is designed and cut to reduce girthwise tension.

Another object of my invention is to provide a pair of shorts which may be adjusted to fit various waist sizes, such adjustable means not requiring the use of any elastic materials.

A still further object of my invention is to provide a pair of shorts having adjustable features and cut to provide roominess in the seat and hip portions without producing a bulky effect.

It is also an object of my invention to provide a pair of shorts which permit great freedom in the body movements and maximum comfort to the wearer.

15 A further object of my invention is to provide a pair of shorts which will give roominess in the seat without requiring the usual so-called "balloon seat."

20 With the foregoing general objects, features, and results in view, as well as certain others which will be apparent from the following explanation, the invention consists in certain novel features and design, construction, and combination of elements, as will be more fully referred to and specified hereinafter.

Fig. 1 illustrates the pattern for the garment including the waistbands and the fly facing.

Fig. 2 is a perspective view of a pair of shorts embodying my invention.

Fig. 3 is a side elevation of a pair of shorts.

Fig. 4 is a side elevation of a pair of shorts in position assumed when the wearer is seated.

Fig. 5 is a view taken on line 5—5 of Fig. 3.

35 Fig. 6 is a perspective view of a pair of shorts embodying a modified form of my invention.

Fig. 7 is a perspective view of a pair of shorts embodying a further form of my invention.

Fig. 8 is a view taken on the line 8—8 of Fig. 6.

Fig. 9 is a view taken on the line 9—9 of Fig. 6.

Referring to the drawings, and particularly

Fig. 1 thereof which illustrates the pattern from which the preferred form of my shorts is cut, the numeral A is used to designate the rear panel or seat portion of the shorts. Two identical sections B and C form the front, leg and hip portions of the shorts when the cut material is sewed together into a completed garment. The waistband of the garment is formed from two strips cut following the pattern sections D and E, and a fly facing F is provided to cover the front opening in the shorts.

The identical panels B and C are provided with elongated V-shaped outwardly diverging openings G which extend from a point spaced from one edge of the panels, which I shall term the

longitudinal edge, to the opposite longitudinal edge thereof. Each transverse edge of the panels B and C are provided with cut out portions H. This pattern is an example of one from which shorts embodying my invention may be cut. However it is to be understood that a variety of undergarments may be provided with the features of my invention.

The completed garment which has been cut from the pattern of Fig. 1 of the drawings and then sewed together is disclosed in Fig. 2. Referring particularly to Figs. 2 and 3 of the drawings it will be seen that the shorts embody side portions 1 which form the hip and thigh coverings and which were cut from the panels B and C of the pattern, and the seat portion 3 which was cut from the panel A of the pattern.

At opposite sides of the garments I provide apertures 5 which were cut into the sides 1 of the garment by following the apertures G in the pattern. Such apertures or side openings are not merely slits in the garment. Instead the material is actually cut out of the garment in such manner as to provide openings which diverge toward the top of the garment before the garment sections are sewed together. Obviously, the garment sections prior to being sewed together to form the finished garment will be similar in all respects to the pattern of Fig. 1. The material may be folded over and stitched to finish the opening if preferred, instead of cutting out the material.

The waistband of my shorts is made in two sections, a front section 7 and a rear section 9. The sections 7 and 9 being so assembled with the garment that each waistband section will extend around the top of the garment from one side opening to the other. Buttons 11 are provided on each end of the rear waistband section 9 and complementary button holes 13 are provided on the front waistband 7. While I show buttons being used in the drawings, it is to be understood that snap fasteners or the like may of course be used. While I preferably provide three buttons and two button holes I may vary these numbers in order to change the range of adjustability without departing from the spirit and scope of my invention.

The shorts of my invention are put on and removed from the wearer by buttoning and unbuttoning the front and rear waistband sections 7 and 9. There is no waistband opening or buttons in the front of the garment which enhances the appearance thereof. A front opening formed by the cut-out portions H as illustrated in the pattern of Fig. 1 is covered by the facing 15 formed from the pattern piece F.

The side openings 5 extend from the top of the garment to a point spaced from the bottom of the garment. Thus the openings extend completely through the plane of the garment seat where expansion is required for comfort when the wearer of the garment is in seated or bent over positions. Actually the side openings 5 extend to within approximately three inches of the bottom of the garment, that is, to a point below the garment crotch seam 6. Now the fact that the openings are of substantial length relative to the length of the garment is of importance as it permits of greatest relaxation of girthwise tension in the seat portion of the garment without requiring extra material or without requiring the customary so-called "balloon seat," or other adaptations thereof.

By means of my invention great savings in

stock may be realized in the manufacture of such undergarments covering the full range of sizes. For example, it can readily be seen that instead of requiring nine (9) sizes to cover a range from size twenty-eight (28) to forty-four (44), a garment embodying my invention would only require four (4) different sizes, to cover the range of sizes.

Fig. 4 of the drawings discloses the action of 10 the garment under the tensions set up therein when the wearer is seated. In this view it is seen that the openings 5 have the greatest expansion in the plane of the central seat area, hence the girthwise tension will be greatly reduced, if not eliminated and the wearer will experience unusual comfort.

I have discovered that by cutting out a V-shaped section of material to make side openings 5 of upwardly diverging shape a greater degree 20 of relaxation of girthwise tension may be had, and I have also discovered that only by making the openings 5 of substantial length relative to the garment length may true relaxation of girthwise tension be obtained.

For adjusting the waist size of my shorts it 25 is only necessary to utilize one of the buttons 11 in a particular buttonhole. As shown in Fig. 4 of the drawings the garment is adjusted to its largest size, while buttoning the button the nearest 30 the rear of the garment in the buttonhole nearest the front thereof will reduce the waistband to the smallest size possible.

By utilizing two buttonholes on the waistband 35 in conjunction with the plurality of buttons I obtain advantageous results which provide a neater garment. Thus if the garment is worn for a smaller size one of the buttons not being used may be inserted in the free buttonhole 40 which will prevent the free end of the rear waistband from folding over.

It is to be understood that a garment having 45 side openings comprising merely a slit or a cut in the material as contrasted with my particularly designed cut-out section with upwardly diverging edges will not expand or provide the same degree of girthwise expansion. Hence, I have devised a manner of providing side openings which will permit the maximum degree of 50 material expansion in the seat portion of the garment.

The side openings 5 are closed at the lower 55 ends thereof by the material of which the garment is made, while at the upper ends thereof they are closed or regulated by the waistband adjusting means. Yet with the waistband adjusted to its smallest position the girthwise tension will be relaxed due to my particular construction of side openings 5, which have been described.

Fig. 5 of the drawings illustrates the particular 60 manner in which the waistbands which are formed of a strip of material doubled on itself, to form a tube are sewed on the body portion of the garment. A row of stitching 19 provides a 65 reinforcing edge 17, and such stitching also aids in providing a unitary waistband structure formed of the doubled-over material. The free edges of the waistband are folded inwardly and the upper edge of the sections are placed between 70 such inwardly folded edges and secured thereto by stitching 21.

In Fig. 6 of the drawings I disclose a modified 75 form of my invention in which the side openings 5 are of substantially similar form and structure, as those of the preferred embodiment of my

invention. However, in this form of invention I eliminate the buttons and buttonhole waistband adjusting means.

Referring particularly to Figs. 6 and 8 of the drawings it will be seen that in this form of my invention I incorporate with the garment a pair of drawstrings 23, one drawstring being attached to each end of the waistbands 7 and 9. The waistbands as have been described are of roughly tubular formation (see Fig. 5 of the drawings) and in the hereinbefore described preferred form of the invention are, of course, stitched at their ends to enclose the area between the folded-over pieces of material of which the waistbands are formed. In the form of my invention now being described the top or folded edges of the waistbands 7 and 9 are not stitched as at 19. A drawstring 23 is inserted a distance within the tubular portion of each waistband at the ends thereof in contact with the folded upper edge, and is secured thereto at its ends by means of a transverse line of stitching 25. A longitudinal line of stitching 27 extends from the transverse line of stitching 25 to the outer end of each waistband, running along and adjacent to but not stitched to the lower edge of the drawstring. This provides a pocket or channel within a portion of each waistband for the drawstring. With the drawstrings or cords attached within the waistbands as described the drawstrings extend from the tubular waistbands, and opposing drawstrings are tied together and the garment is therefore adjustable to fit varying waist measurements.

Considerable flexibility of adjustment is provided by this arrangement of drawstrings, it will be evident from consideration of the drawings that the range of waist adjustment on each side will be equal to twice the distance at which each drawstring is sewed into the tubular waistband.

In Fig. 7 of the drawings I have disclosed a conventional pair of shorts having the usual front opening 29 regulated by buttons 31. In this form of my invention I do not provide waistband adjusting means but I do provide the side openings 5 for reducing girthwise tension. Such openings are of generally similar form and construction as those used in the preferred form of my invention, except that they merely extend to the waistband 33, the waistband being formed in one piece, and they overlap at the waistband as shown.

It will thus be seen that I have discovered a shorts structure which combines waist adjustment means with means for reducing girthwise tension which are cooperatively associated so that one does not hamper the operative characteristics of the other. In the preferred arrangement it will be seen that the upper edges of the material defining the side openings 5 overlap

when a button 11 is inserted in a buttonhole 13, yet due to the particular shape and conformation of the opening there will continue to be a substantial reduction of girthwise tension. Similarly, when the waistbands are adjusted for maximum waistband size the degree of expansion of the opening will be at a maximum which is as it should be due to the fact that the larger the waist of the wearer the greater the girthwise tension.

In the form of the invention of Fig. 6 the upper edges of the material defining the side openings do not overlap, hence such problems as just described are not encountered, therefore a considerable degree of adjustability may be obtained.

I claim:

1. A garment of the character described, comprising a garment body having oppositely disposed side openings therein extending through the upper edge of the garment body and extending downwardly therefrom through the plane of the seat area of the garment to a point below the garment crotch seam, separate front and rear waistbands secured to said garment body in position thereon extending from one side opening to the other, and means for releasably and adjustably securing opposing ends of the separate waistbands together for adjustment of waistband size of the garment.

2. A garment of the character described, comprising a garment body having oppositely disposed side openings therein extending through the upper edge of the garment body and extending downwardly therefrom through the plane of the seat area of the garment to a point below the garment crotch seam, separate front and rear waistbands of tubular construction secured to said garment body in position thereon extending from one side opening to the other, and a drawstring secured at one end only within each tubular waistband at a point therein spaced from the waistband end, and extending from the ends of each waistband, whereby the waist size of the garment may be adjusted by joining the drawstrings extending from opposed waistband ends.

3. A garment of the character described, comprising a garment body having a waistband encircling the upper edge thereof and having a front opening, the garment body having oppositely disposed side openings therein extending from the waistband downwardly of the garment body through the plane of the garment seat area to a point below the garment crotch seam, whereby freedom of movement will be afforded the wearer by reduction of girthwise tension in the garment.

CORNELL M. MILLER.
